UNITED STATES PATENT OFFICE.

WILLIAM F. MORAN, OF CHICAGO, ILLINOIS, ASSIGNOR TO V. B. M. COMPANY, A CORPORATION OF ILLINOIS.

DRIVING MECHANISM FOR WASHING-MACHINES.

1,393,957.

Specification of Letters Patent.

Patented Oct. 18, 1921.

Application filed July 23, 1919. Serial No. 312,654.

To all whom it may concern:

Be it known that I, WILLIAM F. MORAN, a citizen of the United States, and a resident of Chicago, in the county of Cook and 5 State of Illinois, have invented certain new and useful Improvements in Driving Mechanism for Washing-Machines, of which the following is a description, reference being had to the accompanying drawing, which 10 forms a part of my specification.

My invention relates more particularly to the automatic reversing mechanism for driving the drum or dasher, or other suitable agitating element, of a washing machine, whereby a predetermined amount of 15 movement or rotation, in given directions, is provided. The invention has for its object the provision of means whereby the power-imparting mechanism for the drum 20 or dasher will be maintained in positive operative relation, under all conditions, until the reversing elements of the driving mechanism are brought into a certain relation, thus insuring positive rotation of the drum 25 or dasher.

The objects and advantages of my improved mechanism will be more fully comprehended from the detailed description of the accompanying drawing, wherein:—

30 Figure 1 is a side elevation of my improved mechanism with the housing or casing and portions of the mechanism shown in section.

Fig. 2 is a detail sectional view taken on 35 the line 2—2 of Fig. 1 with the housing and gearing omitted.

Fig. 3 is a detail view of a portion of the driven shaft.

The mechanism is adapted to be inclosed 40 in a suitable housing, partially shown at 10, which is intended to be secured to the end wall of the tub or water-holding portion of a washing machine; the mechanism being intended to properly rotate or agi-

45 tate the drum or dasher within the washing machine. The mechanism is intended to be power-driven, generally by means of a suitable electric motor not shown, whereby power is transmitted to the vertically disposed shaft 11 which extends into a suitable housing or gear-casing 12, which is provided with suitable screw gearing whereby the driven shaft 13 is operated. The housing 10 provides suitable bearing for the 50 shaft 13, which is provided with bevel gears

14 and 15 secured at proper distances apart and loosely mounted on the shaft; the spacing of the gears 14 and 15 being commensurate with the diameter of the large gear 16 which latter is secured to the end of a 60 suitable stub-shaft, not shown, so as to cause rotation of the latter and therefore also of the drum or dasher which is controlled thereby. With the gears 14 and 15 meshing with the large gear 16 at opposite 65 sides of the center thereof, it is evident that gear 16 will be given opposite rotation by the gears 14 and 15 when the latter are alternately brought into operative relation with the driven shaft 13.

The driven shaft 13 is preferably provided with an intermediate square section 17, see Fig. 3, at a point intermediate of the gears 14 and 15; and this square section 17 is provided with a double clutch element shown 70 in the nature of an elongated sleeve 18, 75 slidably mounted on the square section 17 of the driven shaft 13 and caused to rotate therewith. The ends of the sleeve are provided with clutch elements 19, 19 adapted to 80 form interlocking or clutching engagement with the lugs or clutch surfaces 20 and 21 secured to or formed on the gears 14 and 15 respectively. The clutch element or sleeve 18 is shown provided with circumferential 85 flanges 22, 22 arranged in spaced relation at an intermediate point, between which is operatively disposed a yoke member or shoe 23 which has threaded relation with the screw or shaft 24 disposed parallel with the 90 driven shaft 13. The screw or shaft 24 is rotatably mounted in the casing 10 and is rotated by means of a pinion 25 secured to gear 14 and meshing with the gear 26 on the screw or shaft 24 thus causing the latter to 95 rotate during rotation of large gear 16, or in other words during rotation of bevel gear 14.

With this construction it is evident that the yoke or shoe 23 (being held against rotation by its straddling relation with sleeve 18) is caused to move lengthwise of screw or shaft 24 during the rotation of the latter; and by reason of screw or shaft 24 being controlled by gear 14, it is apparent that screw 100 or shaft 24 will be caused to rotate alternately in opposite directions, so that the shoe or yoke 23 will alternately be caused to move in opposite directions lengthwise of shaft 24.

The shoe or yoke 23 is shown provided 110

with oppositely disposed pins 27 and 28, both slidably mounted in the lower end of the yoke or shoe so as to engage with the circumferential flanges 22 on the clutch sleeve 18. The pins 27 and 28 are maintained under pressure by means of the flat springs 29 which cause the pins to normally protrude beyond opposite sides of the yoke or shoe, that is, pin 27 protrudes toward the right of yoke 23, in Fig. 1, while pin 28 protrudes toward the left in said figure, so as to engage with the respective flanges 22 on clutch sleeve 18 in advance of yoke or shoe 23. The pin disposed in the direction of movement of the yoke or shoe will be caused to engage with the adjacent flange 22 and thereby place the spring of said pin under increased tension so that when the clutch element is disengaged from either gear 14 or 15, the respective pin will induce a final seating or interlocking relation of the clutch element with the gear or pinion toward which the clutch element has been initially shifted through the action of the yoke or shoe 23.

The mechanism thus far described comprises the subject matter of my application filed September 9th, 1918, and bearing Serial No. 253,223; and it is in connection with the improved mechanism shown and described in said application that the improvement herein to be described is to be employed.

In order to prevent the possibility of the clutch element being prematurely forced out of clutching relation with the respective gears or pinions, due to the action of the spring-controlled pins or plungers carried by the yoke or shoe, especially where the machine may be running under a light load, I provide the clutch sleeve 18, at any suitable point intermediate of the circumferential flanges and one end thereof, with a pin or plunger 30 slidably mounted in a suitable aperture in the sleeve, with its inner end preferably tapered or beveled and arranged to enter either one of a pair of slight depressions or sockets 31 formed in the square section 17 of the driven shaft 13. The depressions or sockets are preferably likewise formed with tapered or beveled sides so as to permit the pin or plunger 30 to be forced out of the depressions or sockets upon due pressure being applied to the clutch sleeve 18 through the action of the yoke or shoe 23. The plunger or pin 30 is yieldingly maintained in inward or depressed position by means of a suitable spring, as for example a flat spring 32; one end whereof is secured to the clutch sleeve 18 in any suitable manner as for example by the set-screw 33 so as to leave the opposite or free end of the spring, to which the pin or plunger 30 is secured, to flex or yield upwardly or away from the clutch sleeve 18. The square section 17 of the driven shaft 13 is provided with a pair

of depressions or sockets 31 arranged in longitudinal alignment and at suitable distances apart commensurate with the degree of maximum movement permitted to clutch sleeve 18 intermediate of gears 14 and 15, see Figs. 70 1 and 3. With this arrangement, it is apparent that when the clutch element or sleeve 18 is at its extreme right hand position, as shown in Fig. 1, the plunger or pin 30 will be in engagement with the right hand depression or socket 31; while on the other hand, when the clutch element or sleeve has been moved to its extreme left hand position, the pin or plunger 30 will be in engagement with the left hand depression or 80 socket.

The spring 32 is of a tension sufficient to maintain the pin or plunger 30 in either one of the sockets or depressions against the action of the spring-controlled plungers 85 27 and 28 and will therefore maintain the clutch element or sleeve in operative relation with the pinion or gear 14 or 15, as the case may be, until the yoke or shoe positively forces the clutch element or sleeve 18 90 in the direction of movement of the yoke or shoe; the movement being induced when shoe 23 bodily engages either flange 22 of sleeve 18. The tapered or beveled end of the pin or plunger 30 will permit shifting of the clutch element or sleeve when due pressure is applied thereto; during which movement the inner end of the pin or plunger 30 will be caused to slide along the shaft-section 17 until it reaches the point of the adjacently 100 placed depression or socket 31.

With this construction, any tendency of the spring-controlled pins or plungers 27 and 28 to force the clutch element or sleeve 18, especially in situations where the washing machine is running with what might be termed a light load, will be guarded against, so that the drum or dasher will at all times be given a predetermined number of rotations or movements in alternate directions, commensurate with the ratio between the gears or pinions 14 and 15 and large gear 16.

The construction shown and described I believe to be the simplest and best adaptation of the invention which, however, is susceptible of modification without departing from the spirit of my invention.

What I claim is:

1. In mechanism of the class described, 120 the combination of a driven-shaft, a pair of gears loosely mounted thereon, a circumferential gear with which said first mentioned gears mesh but at opposite sides of the axis thereof, a double clutch element slidably mounted on the shaft intermediate of said pair of gears, means, controllable through the rotation of one of said gears of the pair of gears, whereby the clutch element is actuated, said means comprising yielding por- 130

- tions adapted to contact with said clutch element in advance of the major portion of said means, and to induce final movement of the clutch element into positive operative relation with the selective gear of said pair of gears, and yielding means whereby said clutch element is held against the action of said yielding portions until said major portion of said first means is brought into positive relation with said clutch element.
2. In mechanism of the class described, the combination of a driven-shaft, a pair of gears loosely mounted thereon, in spaced relation with each other, a double clutch element slidably mounted on said shaft intermediate of said gears, the clutch element and shaft being caused to rotate together, means adapted to have yielding and positive engagement with the clutch element whereby the clutch element is alternately shifted into clutching engagement with one of said pair of gears, with means mounted on said clutch element and having operative relation with the driven-shaft whereby the clutch element is yieldingly locked in its adjusted positions on said shaft until said first mentioned means is brought into positive operative relation with said clutch element.
3. In mechanism of the class described, the combination with a driven shaft, a pair of gears loosely mounted thereon, in spaced relation with each other, a clutch element disposed intermediate of said gears and slidably mounted on said shaft so as to rotate therewith, and clutch-shifting means provided with spring-controlled plungers adapted to have advance engagement with the clutch element and induce final movement of the clutch element into operative relation with the selective gear of said pair of gears, of a spring-controlled element secured to said clutch element and adapted to have operative relation with said driven shaft so as to maintain the clutch element in its adjusted position against the initial action of the spring-controlled plungers of said clutch-shifting means.
4. In mechanism of the class described, the combination of a driven-shaft, a pair of gears loosely mounted thereon, in spaced relation with each other, a double clutch element disposed intermediate of said gears, in slidable relation with the driven shaft so as to rotate therewith, clutch shifting means, alternately movable in opposite directions, said means being provided with a pair of spring-controlled members on opposite sides of said means adapted to engage with the clutch element in advance of the main portion of the means, to be compressed thereby, whereby final movement of the clutch element into complete clutching position is induced, and a spring-controlled pin disposed through said clutch element so as to engage with said driven shaft, the driven shaft being provided with pin-receiving portions at predetermined points correlated to the maximum degree of movement of said clutch element, whereby the clutch element is maintained in adjusted position against the action of the spring-controlled members of said clutch-shifting means until the clutch element is positively engaged by said clutch-shifting means.
